(57) **CLAIM**

I claim the ornamental design for a fishing jig, as shown and described.

DESCRIPTION

FIG. 1 is a perspective view of a first embodiment of a fishing jig showing the new design;

FIG. 2 is a front elevation view of the fishing jig of FIG. 1; FIG. 3 is a rear elevation view of the fishing jig of FIG. 1; FIG. 4 is a left side elevation view of the fishing jig of FIG. 1;

FIG. 5 is a right side elevation view of the fishing jig of FIG. 1;

FIG. 6 is a top plan view of the fishing jig of FIG. 1;

FIG. 7 is a bottom plan view of the fishing jig of FIG. 1; FIG. 8 is a perspective view of a second embodiment of a fishing jig showing the new design;

FIG. 9 is a front elevation view of the fishing jig of FIG. 8; FIG. 10 is a rear elevation view of the fishing jig of FIG. 8; FIG. 11 is a left side elevation view of the fishing jig of FIG. 8;

FIG. 12 is a right side elevation view of the fishing jig of FIG. 8;

FIG. 13 is a top plan view of the fishing jig of FIG. 8; and, FIG. 14 is a bottom plan view of the fishing jig of FIG. 8. Broken lines shown immediate adjacent shaded areas represent bounds of the claimed design and unclaimed features. All other broken lines are directed to unclaimed features. The broken lines form no part of the claimed design.

1 Claim, 14 Drawing Sheets
